UNITED STATES PATENT OFFICE.

JOHN HENRY IRWIN, OF MORTON, PENNSYLVANIA.

STOVE.

SPECIFICATION forming part of Letters Patent No. 226,520, dated April 13, 1880.

Application filed August 8, 1879.

To all whom it may concern:

Be it known that I, JOHN H. IRWIN, of Morton, in the county of Delaware and State of Pennsylvania, have invented a new and useful Improvement in Stoves for Cooking or Heating Purposes, especially adapted to those stoves which employ liquid or gaseous hydrocarbon for fuel.

For convenience, the following description 10 will be confined to an apparatus in which liquid hydrocarbon is employed as fuel; but, as will be apparent, the same principles of structure and operation will be equally applicable and equally effective when fuels of other descriptions are employed.

In all stoves wherein liquid hydrocarbon is employed as fuel it has heretofore been impossible to prevent the flame from giving off jets of smoke under certain conditions, and 20 those jets of smoke are not only unpleasant and objectionable in themselves, but they taint the food which is being cooked, especially in the oven, and are an actual waste of fuel. These jets of smoke are the result of atmospheric disturbances acting upon the air-currents 25 passing to the flame and supporting combustion, and are the distinct result of a deficient supply of air and imperfect combustion. They are caused by disturbances and 30 currents in the adjacent atmosphere, as when the stove is exposed to motion or to wind, or when bodies in the vicinity are moved rapidly, and by the disturbance of the escaping currents by the sudden movement of the oven- 35 door, or the stove-furniture, plates, &c. In fact, any cause which effects a disturbance of the air-currents within or adjacent to the stove will produce the objectionable effects above mentioned.

40 In practice, however, these causes of disturbance are susceptible of separate treatment.

The purpose of my invention is to prevent these objectionable effects by applying to the combustion-chamber and oven of a stove devices which will control the atmospheric currents when disturbed and compel them to aid and facilitate combustion and never to retard it, so that whether the stove shall be exposed to motion itself, or to wind, or to local atmospheric currents caused by the moving of the stove-furniture or bodies in the vicinity, the

air-currents which support combustion will be accelerated and the flame will not be caused to smoke.

The purpose of my invention is, in general 55 terms, effected by a system of counterbalancing air-currents conducted through conduits or air-tubes with injectors and ejectors, such as have heretofore been invented and secured to me by several Letters Patent of the United 60 States.

I therefore do not propose herein to claim anything as to the general method of operation or effect in controlling air-currents for the continuous support of combustion, but design 65 to confine myself to the application and adaptation of the principles of my above-named inventions to the purposes of a stove for heating or cooking, the same being a branch of art and manufacture distinct from that of illumination, although the same general principles, 70 chemical and mechanical, are involved in both.

Disturbances arising from the motion of the oven-door, cooking-utensils, &c., do not, however, require for their correction the presence 75 of injectors and ejectors, because, whereas the effect of such movement heretofore has been entirely to retard the escape of the products of combustion, with my improvement such movements have an effect to accelerate such 80 escape through the action of the counterbalancing air-tubes.

My invention also includes various matter 85 of structural detail, which will be particularly pointed out hereinafter.

Having now set forth the nature and scope of my invention, I will describe more particularly how it may be put into effective operation for the purposes named, having reference to the accompanying drawings, wherein— 90

Figure 1 is a perspective view of a cooking-stove constructed according to my invention. Fig. 2 is a vertical section of the same. Figs. 3, 4, and 5 are modifications illustrating certain differences in the mode of construction 95 with reference to the conduits for the entering air, but without reference to any other part, and without introducing any variation in the mode of operation.

A is an oil pot or reservoir, which, in portable stoves, will be preferably placed in the base, as shown; but for larger and perma-

nently-placed stoves the reservoir may be at a distance, and the liquid fuel may be conducted to the burners by means of pipes. B is a burner set upon said oil-pot, or receiving oil from the reservoir wherever it may be located. Combustion takes place in said burner in the usual way. D is a draft-chimney placed above said burner for the purpose of inducing a sufficient supply of air to flow to the flame. E is the supporting frame-work about and above the top of the chimney, to support the cooking-utensils, &c. These parts are, in general terms, common to all stoves of this class; but their particular structure is not the same in all respects as in other stoves, and their relations with the devices invented by me for the purpose stated are entirely new.

It is now well known that the continuous maintenance of combustion in a burner for liquid hydrocarbon under all conditions of disturbance requires that the air to support combustion shall be received at a point so near to and in such communication with the outlet for the products of combustion that both influx and efflux shall be equally affected by any external atmospheric disturbance, and the supply of air to the flame will be accelerated thereby, though an inferior arrangement of air-inlets nearer to the level of the flame may be used with tolerable success in overcoming some of the external atmospheric disturbances. I therefore place the cone b of the burner B upon the roof of the air-chamber F, which is so located as to surround the burner B. All the air which enters the cone b to support combustion is therefore received from said air-chamber, and the top of the oil-pot is thereby kept cool.

The air which enters the air-chamber is received through air conduits or tubes, which extend from the air-chamber F upward to the immediate vicinity of the outlet of the chimney D.

I prefer to construct with the frame E a chamber, H, to receive the products of combustion from the chimney and the fresh air from outside.

Round the edge of the chamber H, or at convenient points, openings are made in said chamber H to admit fresh air for the feeding-tube, and said openings may be provided with injecting and ejecting devices, whereby exterior air-currents are induced to enter said chamber and the products of combustion are induced to escape, though for the mere purpose of neutralizing the disturbance from the movements of the oven-door or furniture of the stove these injectors and ejectors are not required. The holes e e, armed with deflecting-plates f, are intended for this purpose, though the particular arrangement of the inlets and of the injectors and ejectors may be so greatly varied that I do not propose herein to enumerate them all, but to reserve the right to make special structural arrangements of them the subjects of other patents.

The air-conduit may be annular or other-

wise. I prefer to make said conduit tubular, as at G, and the number of such tubes may be as great as may be necessary.

Independent or accessory injecting and ejecting devices may be placed upon the tube G, as at g, if desired.

In the drawings two varieties of injecting and ejecting devices are shown, merely by way of illustration. In Figs. 1, 2, 4 a complete and perfect injector and ejector is shown at g upon the tube G. A similar perfect injector, annular as to the chamber H, is shown in Fig. 3 at h. In Figs. 1 and 2 a more simple form of injector is shown at f, and either form may be continuous or in sections, according as the opening is continuous or in series.

The chimney D is provided with a jacket, d, attached to said chimney at its lower end and to the bottom plate of the chamber H at its upper end, so that said chimney is suspended and supported within said jacket from above, and at its lower end it does not touch the cone b, and therefore no heat is transmitted from said chimney to said cone. The intervening space, however, is adjusted to admit that volume of air which ought to be admitted above the cone B.

The jacket d prevents a loss of radiant heat from the hot chimney by inclosing a body of air which is in connection with the air within the chamber H, and therefore in active circulation therewith. The upper plate, E, or frame of the chamber H is provided with openings i to admit the cooking-utensils, and suitable covers are provided for said openings.

Any desired number of burners B, with their chimneys, and a requisite number of air-conduits within the injectors and ejectors, may be associated in a single structure to constitute a stove; but for ordinary purposes a stove with three burners is best adapted, and when placed equidistant from each other it admits of the use of an oven over one burner without in any way interfering with the independent employment of the other burners for other purposes. Such a structure is shown in Fig. 1. The ordinary oven employed with hydrocarbon and gas stoves may be employed, as shown at J, Fig. 1.

In Fig. 5 the air-conduit is represented as annular to the chimney D.

Having described my invention, what I claim as new is—

1. A lamp having a burner, B, provided with a slotted cone, and an air-chamber, F, which delivers air beneath said cone only, and an air conduit or tubes to convey air to said chamber, combined with a surmounting frame, E, having one or more holes for the reception of cooking-utensils, whereby a lamp-stove is constituted, as set forth.

2. A lamp having a burner, B, provided with a slotted cone, and an air-chamber, F, which delivers air beneath said cone only, and a surmounting frame, E, provided with holes for the reception of cooking-utensils, combined with air conduits or tubes extending from said

- chamber to the vicinity of the outlet of said chimney.
3. A stove for heating and cooking purposes having a top provided with one or more holes for the reception of cooking-utensils, combined with one or more burners and chimneys, and an air-chamber, F, below the slotted cones of said burners, and which delivers air to the flame only, air conduits or tubes, and devices for injecting and ejecting air into said air-chamber and out from said chimney, respectively, substantially for the purpose set forth.
4. A stove for heating and cooking purposes with a top provided with one or more holes for the reception of cooking-utensils, combined with burner B and chimney D, and with the air-chamber F, and air conduits or tubes provided with injectors and ejectors to inject air into the conduit and eject air from the chimney, respectively, as set forth.
5. A stove for heating and cooking purposes having a chamber, H, at the top, provided with holes for the reception of cooking-utensils, and holes e, armed with injecting and ejecting devices around their edges, combined with the burner B, with its chimney D, and with the air-chamber F, and air tube or tubes G, connecting said air chamber with the chamber H, as set forth.
6. In a stove for heating or cooking purposes, a chamber, H, at the top, having holes for the reception of cooking-utensils, and burner B below said chamber, combined with the chimney D, having the jacket d, whereby 35 said chimney is suspended and inclosed, so that heat radiated from the wall of said chimney is saved, as set forth.
7. In a stove for heating or cooking purposes, a chamber, H, at the top, having holes 40 for the reception of cooking-utensils, and burners B below said chamber, combined with chimney D and jacket d, whereby said chimney is suspended from above the burner-cone b and disconnected therefrom, as and for the 45 purpose set forth.
8. In a stove for heating or cooking purposes, a chamber, H, at the top, having holes for the reception of cooking-utensils, and burner or burners B below said chamber, combined with chimney or chimneys D, suspended from above the burner-cone b and disconnected therefrom, as and for the purpose set forth.

J. H. IRWIN.
